George Hayes.

UNITED STATES PATENT OFFICE.

GEORGE HAYES, OF NEW YORK, N. Y.

IMPROVEMENT IN PANELS FOR BLINDS.

Specification forming part of Letters Patent No. 173,789, dated February 22, 1876; application filed January 17, 1876.

To all whom it may concern :

Be it known that I, GEORGE HAYES, of No. 71 Eighth Avenue, in the city, county, and State of New York, have invented a new and useful Improvement in Panels for Window-Blinds, Shutters, Doors, Screens, Shades of Railroad-Cars, and to take the place of movable or stationary slats in every instance where they may be used; and I do hereby declare that the following is a full, clear, and exact description of the same, reference being had to the accompanying drawing, which forms part of this specification.

This invention has for its object, or certain of them, the same as those described in my former application for patent filed in the Patent Office October 23, 1875, namely, to obstruct the direct rays of the sun, and to exclude dust, insects, &c.; and as I propose using narrow strips of metal, I can construct the panels of smaller pieces or cuttings of the sheets which have been used for other purposes—consequently a saving in cost is effected.

My improvement consists in forming a panel composed of a strip of perforated metal one inch in width, more or less, and another strip of blank metal of corresponding or suitable

width, the edges of which I bend so as to form a bearing or shoulder, upon which the perforated strip rests, and when necessary to increase the strength of these strips, I propose to press them widthwise into a segmental form. I then place these strips of metal in a frame of a blind or door, securing their ends in any suitable manner.

Referring to the accompanying drawing, Figure 1 represents a front view of a panel. Fig. 2 represents a vertical section of same.

Similar letters of reference indicate corresponding parts.

A is the frame to which the strips of metal are secured; B, the perforated strips of metal; C, the blank strips of metal.

What is here claimed, and desired to be secured by Letters Patent, is—

A panel composed of strips of perforated metal and blank strips of metal bent into form substantially as and for the purpose herein shown and described.

GEORGE HAYES.
